UNITED STATES PATENT OFFICE.

JOHN A. DODGE, OF SOMERVILLE, MASSACHUSETTS.

WRENCH.

SPECIFICATION forming part of Letters Patent No. 274,113, dated March 20, 1883.

Application filed July 21, 1882. (No model.)

To all whom it may concern:

Be it known that I, JOHN A. DODGE, of Somerville, in the county of Middlesex and State of Massachusetts, have invented certain new and useful Improvements in Wrenches, of which the following is a full, clear, and exact description.

This improved wrench is composed of a movable and a stationary jaw and a handle-lever. 10 The movable jaw is arranged to be slid along a bar and to be adjusted and set thereon as desired, and this bar passes loosely through the stationary jaw and is engaged with a handle-lever that is fulcrumed to the stationary jaw, 15 and all in a manner that the movable jaw of itself and independently of the stationary jaw can be adjusted in position upon its carrying-bar in relation to the stationary jaw, and then by the swing of the handle-lever in one direction 20 made to approach the nearer to, and in the other direction to recede from, said stationary jaw, substantially as hereinafter described.

In the accompanying plate of drawings this 25 improved wrench is shown as gripping a pipe, and Figure 1 is a side view; Fig. 2, a central longitudinal section; and Fig. 3, a cross-section on line 3 3, Fig. 1.

In the drawings, A represents the handle-lever, B the stationary jaw, and C the movable jaw, making the three parts of the present improved wrench.

The movable jaw C is loose upon a screw-threaded bar, D.

35 E is a screw-threaded nut, interlocking with the jaw G and engaging with the screw-threaded bar D, all so that by properly turning the nut the movable jaw C can be moved along the length of the bar and thus adjusted 40 and set thereon, as may be desired. The bar D passes loosely through the stationary jaw B, so that the holding or gripping faces F and G, respectively, of each jaw are opposite to each other; and the stationary jaw B has two ear-pieces, b b, which project in parallel lines toward and over the upper edge, d, of the movable jaw C. The handle-lever A is placed between the ear-pieces b b, and is hung upon a fulcrum-pin, f, of the stationary jaw B, and 45 by a tooth, g, engaged with a notch, h, in the upper edge, k, of that portion of the screw-

threaded bar D within the stationary jaw B. These ear-pieces b b, when the handle-lever is swung to cause the jaws of the wrench to tightly grasp the article to which it is adjusted 55 and applied, as hereinafter described, come to a bearing and rest against the upper edge, d, of the movable jaw, and thereby, as is obvious, the stationary jaw is held against further movement with the handle-lever as such swing 60 of the lever is continued, securing, as a consequence, the moving of the movable jaw toward the stationary jaw, as hereinafter described.

A wrench constructed as above described, it 65 is plain, allows the movable jaw of itself and independently of the stationary jaw to be adjusted and set upon its bar D to place its gripping-face nearer to or farther from the gripping-face of the stationary jaw, as may be necessary, to accommodate the wrench to its work, when by pulling or pushing upon the handle-lever in one direction the movable jaw will be operated to tightly grip the article between its gripping-face and the gripping-face of the stationary jaw, and in the other direction the same 70 jaw will be operated to release its said grip, so that the wrench may be swung backward upon the article to get another hold thereon for again turning it or to be detached therefrom.

The movable jaw and its carrying-bar D, constructed and arranged, as described, for the adjustment and set of the jaw upon the bar, obviously may be constructed and arranged in 85 other ways and yet secure the same effects upon the jaw—as, for instance, by notching the bar at regular or irregular intervals in its length, and by arranging a spring-lever catch upon the jaw to engage with said notches, and 90 thus hold the movable jaw against movement on its bar, while it will allow it to be adjusted thereon.

The construction and arrangement of a movable and a stationary jaw and a lever-handle 95 substantially as herein described obviously are capable of application to a monkey-wrench or to a pipe-wrench with equal effect and advantage.

Having thus described my invention, what 100 I claim, and desire to secure by Letters Patent, is—

1. The combination, in a wrench, of a stationary jaw, B, a bar, D, loosely carried by the same, a jaw, C, movable with and adjustable along the bar, and a handle, A, pivotally connected with the stationary jaw for moving the bar, substantially as described.

2. The combination, in a wrench, of a stationary jaw, B, a screw-threaded bar, D, loosely carried by the same, and provided near its outer end with a notch or recess, a jaw, C, movable with and adjustable along the bar, and a

handle, A, pivoted to the stationary jaw and provided with a tooth engaging the notch or recess in the bar, substantially as described.

In testimony whereof I have hereunto set my hand in the presence of two subscribing witnesses.

JOHN A. DODGE.
